UNITED STATES PATENT OFFICE.

ROBERT A. MOORE, OF DETROIT, MICHIGAN.

PORTABLE RUBBING MACHINE.

Application filed April 11, 1918. Serial No. 228,018.

To all whom it may concern:

Be it known that I, ROBERT A. MOORE, a citizen of the United States, and a resident of Detroit, county of Wayne, and State of Michigan, have invented a new and useful Improvement in Portable Rubbing Machines, of which the following is a specification, the principle of the invention being herein explained and the best mode in which

10 I have contemplated applying that principle, so as to distinguish it from other inventions.

The present improvements, relating as indicated to portable rubbing machines, are directed to an apparatus that may be operated by a single workman for rubbing down or smoothing painted or varnished surfaces preliminary to the application of the finishing coats. This work is usually done by hand and requires a considerable time, which it is one of the objects of this invention to save by providing a simple and convenient machine which may be operated by a single workman. Other objects of the inventions

25 are the provision of means for supplying a uniform amount of rubbing material to the surface to be worked upon and convenient manual control of the device by the operator. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

40 In said annexed drawing:—

Fig. 1 is a side elevation of my improved apparatus with one of the cover plates removed to show the mechanism; Fig. 2 is an end view of the device looking at the same from the right side of Fig. 1 and from inside the casing; Fig. 3 is a side elevation of the device connected with the supply reservoirs for fluid pressure and surfacing material; Fig. 4 is a section on line 4—4, Fig.

45 1; Figs. 5, 6 and 7 are plan views of rubbing belts showing the various types of re-

cesses formed therein for receiving surfacing material, and Fig. 8 is a section on the line 8—8, Fig. 3. In Fig. 3 the rubbing device 1 is shown connected to two flexible conduits 2 and 3 of which the former is connected to a conduit 4 for supplying suitable fluid pressure, such as compressed air or steam, to the device for operating the motor which will presently be described, while the conduit 3 is connected to a suitable supply reservoir 5 for rubbing or surfacing material suspended in water, such, for example, as pumice stone. A connection 6 from the line 2 extends to the bottom of the reservoir 5 and supplies a small amount of fluid pressure thereto at all times for the purpose of agitating the rubbing material in water and maintaining the proper amount of material in the water which is fed through the line 3, the fluid pressure being discharged into the reservoirs through a distributor 40 having nozzles 41 arranged to impart a circular movement to the liquid and solid matter in the reservoir.

The device itself is best shown in Fig. 1 and consists of a casing or frame 7 in which is housed a suitable fluid pressure motor 8, which may be of any suitable type and which need not be described in detail. The fluid pressure motor 8 receives fluid pressure from the conduit 2 and the exhaust discharged laterally through the sides of the casing 7 through the apertures 9, which are indicated in this figure. Mounted in the casing 7 are a plurality of pulleys or rollers 10 and 11, there being a number of the pulleys 11 which are preferably arranged in the same plane and serve as a support for a portion of a rubbing belt 12, which passes over all the pulleys. The pulleys 11 are preferably constructed in such a manner as to yield axially in the manner described in my co-pending application, Serial No. 209,756, filed December 31, 1917, and since the construction of these pulleys forms no part of the present invention, I have not shown in detail their construction. The pulley 10 is provided with a number of points or teeth 13 which are adapted to engage in suitable formed apertures on the inner side of the belt 12 and in this way positively drives this

belt. I have found it preferable to drive the belt 12 in a positive manner, although it can be operated, if desired, by frictional contact between the pulley 10 and the inner 5 surface of the belt. The pulley 10 is provided on one end with a gear 14, which is engaged and operated by a gear 15 driven by the shaft of the fluid pressure motor 8, and an idler pulley 17 mounted on the interior 10 of the casing 7 serves to maintain the proper tension on the belt 12.

Mounted within the belt 12 is a second belt 18, preferably formed of some material like cork and provided with a number of 15 transverse slits 19 which permit the belt to conform to the surface of the rollers 11 at the ends of the line of these rollers. This belt 18 does not pass over the pulley 10 but merely serves as a support for the belt 12, 20 while the latter passes across the rollers 11.

The pulleys 10 and 11 are mounted on a suitable triangular frame work 20, which is provided on either side with guides 21 engaging in guideways 22 formed in the sides 25 of the casing 7 in the manner shown in Fig. 4. The bottom of the casing 7 is open and the frame 20 with the pulleys and belts may be inserted into this open end and locked therein by means of keys or latches 23. The 30 position of this latch determines the inner position of the framework 20, and this position will be such that, as the framework is moved into the casing, the belt 12 engages against the idler 17 and is tensioned 35 only when inserted in the casing in operative position. When the framework and belts are removed from the casing, the belt 12 is relatively loose and may be readily removed from the pulleys for replacement or 40 repairs.

The conduit 3 supplying surfacing material terminates in a nozzle 25 extending transversely across the upper end of the belt 12 at the point where the latter passes over 45 the pulley 10. The belt makes a very sharp angle in passing over the relatively small pulley 10 so that the belt is bent sharply and this bending opens up slots 26 which are formed in the outer surface of the belt. 50 These slots may be of different forms, as indicated in Figs. 5, 6 and 7, although I have found that a satisfactory form of these slots or recesses is that in which the slots run diagonally across each other, which 55 form is shown in Fig. 5. The water and pumice stone or other surfacing material is fed into these open slots and the action of the belt in closing the slots after each portion leaves the pulley 10 squeezes out the 60 water and retains the pumice stone in these recesses on the belt. In this way the surface of the belt is always supplied with a surfacing material and an even and regular action on the painted or varnished surface 65 is secured.

The operation of the device will be readily apparent from the foregoing description. The operator grasps the device by the handle 30 and moves it over the surface to be treated, controlling the supply of fluid pressure and of surfacing material by throttles 70 31 and 32 disposed in the feed lines 2 and 3 respectively at the points adjacent to the top of the casing 7, in this way varying the speed of the rubbing and also the amount 75 of rubbing material to suit the nature of the work.

The uses to which the present apparatus may be applied are numerous and far more extensive than the single illustrative field 80 here referred to, i. e. the rubbing of painted and varnished surfaces, and these other uses will readily suggest themselves to those skilled in the various arts. Similarly other materials may be supplied to the belt depending upon the particular surface to be treated and the work to be done thereon. 85

Other modes of applying the principle of my invention may be employed instead of the one explained, change being made as 90 regards the mechanism herein disclosed, provided the means stated by any of the following claims or the equivalent of such stated means be employed.

I therefore particularly point out and 95 distinctly claim as my invention:—

1. In a portable hand rubbing machine of the character described, the combination of a frame, a belt and a motor for driving the same operatively mounted thereon, said 100 belt being provided with a plurality of normally closed slots adapted to be opened in their travel through the machine and adapted to receive surfacing material therein when opened, and means adapted to feed surfacing material to such slots in said belt. 105

2. In a machine of the character described, the combination of a frame, a belt operatively mounted thereon, said belt being provided with a plurality of normally closed 110 slots adapted to receive surfacing material therein, said belt being arranged to pass over a relatively small pulley to thereby open such slots, and means adapted to feed surfacing material to such slots when open. 115

3. In a portable hand rubbing machine of the character described, the combination of a frame, a plurality of pulleys mounted therein, a belt passing over all of said pulleys, a second pulley spaced from said first named pulleys, a second belt contacting said first named belt and supporting it against its pulleys and passing over said second pulley, and adapted to drive said second belt and through it said first named belt, and a motor mounted on said frame for driving said second belt. 120

4. In a portable hand rubbing machine of the character described, the combination of a frame, a plurality of spaced pulleys 125

mounted therein, a belt passing over all pulleys, a second pulley mounted on said frame and spaced from said first named pulleys, a second belt contacting said first named belt and supporting it against its pulleys and passing over said second pulley, said second belt and said second pulley being provided with interengaging means adapted to constitute a positive driving connection between said belt and said pulley. 10
5 Signed by me this 16th day of March, 1918.

ROBERT A. MOORE.
